APPARATUS FOR TREATING SEWAGE.

No. 390,168.

Patented Sept. 25, 1888.

UNITED STATES PATENT OFFICE.

S. EMERSON HARTIAN, OF WORCESTER, MASSACHUSETTS.

APPARATUS FOR TREATING SEWAGE.

SPECIFICATION forming part of Letters Patent No. 390,168, dated September 25, 1883.

Application filed March 3, 1887. Serial No. 229,528. (No model.)

To all whom it may concern:

Be it known that I, S. EMERSON HARTIAN, a citizen of the United States, residing at Worcester, in the county of Worcester and State 5 of Massachusetts, have invented certain new and useful Improvements in Apparatus or Plant for Treating Sewage and Water, of which the following, together with the accompanying drawings, is a specification sufficiently 10 full, clear, and exact to enable persons skilled in the art to which this invention appertains to make and use the same.

The object of my present invention is to provide an efficient and economical apparatus or 15 plant for the treatment or purification of sewage and water; and my invention consists in an apparatus constructed and organized for operation as illustrated and explained in the following description, the particular subject- 20 matter claimed being hereinafter definitely specified.

In the drawings, Figure 1 is a plan view illustrating my improved plant for treating sewage. Fig. 2 is a longitudinal vertical section of the same, and Fig. 3 is a transverse section of one of the filter-beds, drawn to a somewhat larger scale.

In referring to parts, A denotes the water course or channel whereby the sewage is delivered to the filtering compartments, which 30 preferably consist of oblong areas inclosed by upright side walls, a, with a bulk-head, B, at the lower end, and having an overflow or roll-way, b, at its top for the discharge of the water. Any desired number of these compartments may be employed, according to the extent of the plant. In the present instance I have shown two compartments arranged side by side, each being provided with a gate, C, 35 for shutting off the passage from the supply-channel A, so that either compartment can be drained while the other is in operation.

D indicates a filter-bed disposed within the compartment, preferably in a more or less oblique or inclined position longitudinally thereof and laterally horizontal. Said filter-bed in the present instance commences at one end near the head of the compartment, at the bottom thereof, and gradually rises to a position 40 near the bulk-head B, where the filter is above the water-level or top line of the bulk-head.

In practice the size of the filter-bed may be eight to ten feet (more or less) in width and from fifty to one hundred feet (more or less) 55 in length.

The filter-bed is supported on suitable framework, E, and may be composed of any suitable material. The construction which I deem best for this filter-bed is illustrated in Fig. 3, wherein e indicates a series of longitudinal boards supported narrow edge upward on the frames E. Upon these are a coarse-mesh grating or netting, d, next a mediumly-fine mesh wire-netting, d', then three courses (more or less) of hair felt, F F' F'', and above these a fine wire- 65 netting, f, and a series of longitudinal iron slats or bars, i. This construction may be modified as desired for effecting equivalent operation.

G indicates an endless belt or chain, composed of a series of transversely-disposed scraping-bars, of wood or other suitable material, linked together, and mounted on guiding wheels or rolls G' and driving-sprocket H, and operated to travel along the top surface of the 75 filter-bed from its lower to its upper end for scraping the deposited sludge or solid material therefrom. The scraping-bars G' of the chain belt slide along the longitudinal slats i, whereby unnecessary wear on the surface of the 80 felt or top netting is prevented.

The traveling chain G of scraping-bars G' transfers the sludge from the filter-bed D to a conductor, I, that leads into a revoluble hydro-extractor or centrifugal machine, J, by 85 means of which the greater portion of the moisture is made so as to be self-discharging—that is, it is discharged from the sludge. Said machine J has a rotatable basket of such form that a constant supply of material may be fed 90 into it from the conductor I, and as the solid material becomes freed from moisture it is caused, by the rotation of the extractor, to work up and over the edge of the basket, and falls into a receiving-space, l, from which it is 95 carried to any desired place of delivery by the endless-band conveyer L. The feeding and discharge of the hydro-extractor is thus rendered automatic and continuous, so that it operates without the necessity of special attention 100 of an attendant. A pipe or conductor, J', leads from the water-space of the extractor mech-

anism into the filter compartment, through which the water extracted from the sludge can flow back to said compartment to be re-filtered.

5 M indicates a driving-shaft, provided with suitable pulleys and belts, $m m' m^2$, for operating the filter-clearing belts G, the hydro-extractor J, and conveyer L.

A turbine water-wheel, N, arranged to take 10 water from the filter compartments below the filter-bed by a suitable gate or gates, as n, is in the present instance provided for operating the apparatus, its shaft N' being provided with suitable pulleys, from which a belt, m^3 , runs 15 to the pulley on shaft M for transmitting power and motion thereto. The driving motor is preferably a water-wheel, as N, in cases where there is sufficient head and fall to give the required power; but a steam-engine or other kind 20 of motor may be used for operating power if more convenient or preferred, and the shafting and pulleys, with their driving belt or gearing, may be disposed in any convenient arrangement.

25 In the operation of my improved apparatus the sewage from the channel A flows onto the top surface of the filter bed or beds D and percolates through the felting, leaving the solid matter or sludge on the top surface of the filter. The water flows over the top of the bulk-head B or through the gate n, and escapes 30 down the channel or tail-race R. The cleaning-belt G, being in action, scrapes the accumulated solid matter or sludge into the conductor I, whence it falls into the central chamber of the extractor-machine J, and is delivered therefrom to the conveyer L, whereby it is carried to the place of deposit, to be burned or disposed of in any manner desired. The 35 operation of the mechanism for filtering and removing the sludge is continuous and automatic, and can be maintained or operated with economy and with but little attention. When

necessary, the gate C can be closed and a compartment drained through the waste-gate s, to 45 facilitate repairs or overhauling the filter-bed while the filter in the other compartment is in operation.

What I claim as of my invention, and desire to secure by Letters Patent, is—

50 1. In combination, substantially as described, the stationary filtering-bed D, the endless traveling clearing-belt G, provided with a series of laterally-disposed scrapers that drag along the face of the filtering-bed, the guiding and operating rolls carrying said belt, a hydro-extractor mechanism into which the sludge is deposited automatically from said clearing-belt, and means for imparting motion to said mechanism, for the purposes set forth.

55 2. In a plant for treating sewage, a filtering-bed constructed as shown and described, and consisting of the transverse frames E, the longitudinal strips e, the gratings d d', supported on the edges of said strips, sheets of filtering material, F, and the longitudinal guard-bars i, extending along the face thereof, in combination with a chain or belt having a series of scrapers that travel along the face of the filter supported by said guard-bars, substantially as 60 70 75 and for the purpose set forth.

3. The within-described purifying apparatus, consisting of the filter-bed D, endless traveling belt G, having scraper-bars G², supported on guide-rolls G', the operating-wheel H, the conductor I, the self-discharging hydro-extractor J, conveyer L, and water return-pipe J', arranged, substantially as shown and described, for treating sewage by continuous action, as set forth.

8c Witness my hand this 26th day of February, A. D. 1887.

S. EMERSON HARTIAN.
